United States Patent Office

Des. 212,491

Patented Oct. 22, 1968

212,491

PIPE LAYER OR SIMILAR ARTICLE

Ralph W. Speiser and William C. Lindquist, Minneapolis,
Minn., assignors to Toro Manufacturing Corporation,
South Minneapolis, Minn., a corporation of Minnesota

Filed Sept. 5, 1967, Ser. No. 8,490

Term of patent 14 years

(Cl. D40—1)

FIG. 3

FIG. 2

FIG. 1

FIG. 5

FIG. 4

FIGURE 1 is a left front perspective view of a pipe layer or similar article embodying the new design;

FIGURE 2 is a rear elevational view thereof;

FIGURE 3 is a front elevational view thereof;

FIGURE 4 is a side elevational view thereof as viewed from the left side of FIGURE 1;

FIGURE 5 is a top plan view thereof.

We claim:

The ornamental design for a pipe layer or similar article, substantially as shown.
